UNITED STATES PATENT OFFICE.

HUGH H. MEEHAN, OF CHICAGO, ILLINOIS.

GOLF DRIVING BOARD.

Application filed September 24, 1927. Serial No. 221,669.

This invention relates to improvements in golf driving boards, and more particularly to a platform from which golf balls may be driven either from the driving tees on a golf course or in an indoor court.

The object of the invention is to provide a suitable teeing surface which will simulate the yieldable character of the natural turf and yet withstand hard usage without appreciable deterioration.

A further object of the invention is to provide a platform or board suitable for installation in indoor practice courts or on the driving tees of outdoor courses, on which the player may stand in addressing and driving the ball, said platform having an especially constructed area on which the ball is placed and having the characteristics already pointed out.

A preferred embodiment of the invention is disclosed in the accompanying drawings, in which

Figure 1 is a perspective view of a driving board in its preferred form.

Figure 2 is an enlarged detail view in longitudinal section as taken on line 2—2 of Figure 1.

Figure 3 is an enlarged top plan view of the driving area of the board showing its construction.

Figure 4 is a detail view in vertical section taken on line 4—4 of Figure 3.

Figure 5 is a perspective view of one of the anchor blocks.

The device in its preferred form comprises in general a rectangular board or platform 1 of such dimensions as to provide sufficient room on which a player may stand in the execution of the driving stroke. The platform is preferably constructed of wood and covered with a suitable material to prevent slipping, such as rubber or composition matting. However, the construction of the board may be as simple or as elaborate as desired.

Near one edge of the platform and extending parallel therewith is a rectangular cavity or recess 2, say eighteen inches long, six inches wide and one and one-half inches in depth, the ends of the cavity being spaced a foot or so from the side edges of the platform.

Lying in this cavity is a rectangular block 3 of a resilient material,—sponge rubber having been found to be a very satisfactory material. The thickness of this block is

substantially equal to the depth of the cavity 2 although its surface is slightly depressed below the level of the platform. The block 3 has the same width as the cavity, but is considerably shorter, thus leaving spaces of several inches between the ends of the block and the adjacent ends of the cavity. The block may be held in place in any suitable manner, since it is intended to remain fixed therein. Extending over the block 3 and substantially the length of the cavity is a strip 4 of flexible material of a suitable kind and quality, a very satisfactory material being a heavy grade of canvas preferably impregnated with paraffine or wax to give it a smooth surface from which the club head will glance more readily on impact.

This strip 4 is substantially the same width as the cavity and is stretched lengthwise thereof and anchored at each end in the following manner:

Both ends of the strip are securely fastened to blocks 5—5 which fit crosswise and in the spaces between the ends of the resilient block 3 and the ends of the cavity, these blocks being slightly less in thickness than the depth of the cavity.

The strip and anchor blocks are assembled as a unit before mounting in the cavity, the following being the preferred method followed:

The blocks are provided on their top faces with a series of parallel semicircular grooves 5^a (Figure 5) extending transversely and spaced apart at intervals. The end portions 4^a of the strip 4 are then doubled back and under, and laid on the grooved face of the block, as shown in Figure 2. A series of rods 6 are then placed over the end portions of the strip and pressed down into the grooves, the latter being enough greater in diameter to permit the material of the strip to enter the grooves. Over the rods and the end portions of the strips are then placed metal plates 7—7 of the same area as the top of the blocks, these plates being securely fastened down to the blocks by rows of screws or bolts 8 either passing entirely through the block as shown, or driven into the blocks. In this manner the anchor plates bear down against the rods 6 which in turn lock the end portions 4^a of the strip securely against displacement, the bolts or screws passing through the strip between the rods and affording additional anchorage.

The blocks, with the strip attached, are

then inserted in the cavity, it being noted that the blocks lie beneath the ends of the free intermediate portion of the strip with the fold lines adjacent the ends of the cavity.

Extending edgewise through the platform from the sides opposite each end of the cavity, is a pair of relatively long bolts 9—9 having hexagonal heads 9^a at their outer ends and threaded portions 9^b at their inner ends. These bolts extend endwise into the cavity and thence through longitudinal bores passing through each of the anchor blocks 5—5 a short distance inwardly from their ends. On the threaded inner ends of these bolts are nuts 10—10 which are countersunk in recesses 5^b—5^b formed in the inner edge of the anchor blocks. The manifest purpose of these bolts is to draw the strip perfectly tight over the cavity and the block of resilient material beneath and to maintain the same at the desired degree of tautness, the arrangement of the bolt at each end making it possible to apply tension from the four corners of the strip.

By reason of the adjustment of the strip, spaces are necessarily left between the anchor blocks and the ends of the cavity. These spaces are preferably covered by strips 11—11 of relatively stiff material, such as sole leather, which are fastened down to the surface of the platform just beyond each end of the cavity, with their free end portions overlying the ends of the strip after the manner of flaps. The free edges of these flaps are preferably beveled so as not to present an edge which might be encountered by the club head in the act of striking a ball, but at the same time, prevent the club head from striking the ends of the anchor blocks in case of a mis-directed swing.

In using the driving board, the ball is placed at the center of the strip, usually elevated upon a tee, and then driven in the usual manner, the club head striking the surface of the strip as it is swung downwardly into contact with the ball, and by virtue of the resilient block beneath the strip, there is sufficient depression of the surface to permit the club head to get under the ball as is the case when driving from turf. The construction of the device is such that the teeing surface is practically indestructible and may be used for an indefinite period without the strip wearing out.

The driving board may be either portable or fastened to the floor when used for indoor play, and for outdoor use would preferably be sunk into the ground to the level of the surrounding turf. Moreover, for outdoor use the platform need only be large enough to house the parts forming the teeing surface, the player standing on the ground in addressing and driving the ball.

Having set forth a preferred embodiment of my invention, I claim:

1. A golf driving board comprising a platform having a cavity in the surface thereof, a block of resilient material mounted in said cavity with its surface substantially flush with said platform, a layer of flexible material extending over said block, and means for anchoring the ends of said layer to said platform. 70

2. A golf driving board comprising a platform having a rectangular cavity in the surface thereof, a layer of resilient material fitting into said cavity to substantially the depth thereof, anchor blocks mounted in said cavity on opposite sides of said resilient material, a strip of flexible material secured at its ends to said blocks, and means for adjusting said blocks to place said strip under tension. 75

3. A golf driving board comprising a platform having a rectangular cavity in the surface thereof, blocks slidably mounted in said cavity adjacent the ends thereof, a strip of flexible material anchored at its ends to said blocks and lying substantially flush with the surface of said platform, and adjusting members mounted in said platform and connected with said blocks. 80

4. A golf driving board comprising a platform having a relatively shallow cavity in the surface thereof, a block mounted adjacent each end of said cavity, a strip of flexible material extending lengthwise of said cavity substantially flush with the surface of said platform and anchored at each end to one of said blocks, and adjusting bolts extending edgewise through said platform and engaging said blocks. 85

5. A golf driving board comprising a platform having a relatively shallow elongated cavity, a strip of flexible material adapted to extend lengthwise of said cavity substantially flush with the surface of said platform, a mass of resilient material filling said cavity intermediate the ends of said strip, and means for adjustably anchoring the ends of said strip to said platform. 90

6. A golf driving board comprising a platform having a shallow cavity terminating at its ends adjacent opposite sides thereof, a strip of flexible material adapted to be stretched over said cavity flush with the surface thereof and slidably mounted adjacent the ends of said cavity and including clamping plates, the end portions of said strip being doubled under and inwardly and clamped between said plates and the top faces of said blocks, and means for adjusting said blocks lengthwise of said strip 120 for increasing and decreasing the tension thereof. 115

7. A golf driving board comprising a platform having a shallow cavity terminating at its ends adjacent opposite sides there- 125

of, a strip of flexible material adapted to be stretched over said cavity flush with the surface thereof and slidably mounted adjacent the ends of said cavity and including 5 clamping plates, the end portions of said strip being doubled under and inwardly and clamped between said plates and the top faces of said blocks, adjusting bolts extend-

ing edgewise through said platform and engaging said blocks, and a body of resilient 10 material mounted in said cavity between said blocks and beneath the central portion of said strip.

Signed at Chicago, Ill., this 12th day of September, 1927.

HUGH H. MEEHAN.
